UNITED STATES PATENT OFFICE

CHARLES A. WAITZ, OF ERIE, PENNSYLVANIA

APPARATUS FOR APPLYING PRESSURE TO OIL SANDS

Application filed October 28, 1925. Serial No 65,335.

It is common practice to place one well under pressure of water or air to realize the effect of such pressure through adjacent wells. Where there are several sands the practice has been to treat the several sands by utilizing a different well for each different sand. The present invention is designed to place pressure on a plurality of oil sands through one well, thus economizing in the wells used for this and also in the apparatus. Features and details of the invention will appear from the specification and claims.

The invention is illustrated in the accompanying drawings as follows:—

Fig. 1 shows a vertical section of the apparatus.

Fig. 2 a section on the line 2—2 in Fig. 1.

Fig. 3 a section on the line 3—3 in Fig. 1.

10 1 marks the upper sand, 2 the second sand, and 3 the third sand of a well 4. The usual casing 5 with the casing head 6 is used.

15 A strainer or perforated tube 7 rests on the bottom of the well. A step or shoulder 8 carrying a rubber packer 9 is arranged on the tube 7 and the packer rubber 9 rests on the shoulder 8. A tube 10 rests on the expanding cone 9a, the tube telescoping the packing rubber in the usual manner of 20 packers as shown in Fig. 3. The packer 9 is above the third sand.

25 A bypass 11 is secured to the tube 10 and a tube 12 extends upwardly from the bypass to a packer shoulder 13. A packer rubber 14 is arranged on the shoulder 13 and has an expander 14a. The packer 14 is above the second sand so that the second sand is between the two lower packers. A tube 15 extends upwardly from the expander 14a to 30 a packer shoulder 16. A packer rubber 17 is arranged on this shoulder. A tube 18 is in continuation of the tube 15 and extends through the casing head 6. It is connected by a pipe 19 with a T 19a and by way of the 35 T 19a with the pressure fluid supply through a pipe 20.

40 A packer 17 is above the first sand. The bypass is preferably arranged at the level of the second sand. It has a pipe socket 21 from which radial openings 22 extend

through a shell 23. Passages 23a are arranged in the pipe socket and the shell 23 and between the walls of the passages 22 forming the bypass for the tube line leading to below the first packer 9. A pipe 24 fits in the socket 21 and extends upwardly through the several tubes 12, 15, 18 and through a stuffing box 25 on the casing head. The pipe extends by a lateral pipe 18a to a T 26 which is connected by a pipe 27 with the T 19a 55 and consequently with the source of supply.

50 The bypass openings 22 are preferably radial so that if any fluid under high pressure, particularly hot liquids are used the liquid will be driven against the sand and 55 thus will cleanse the surface and remove paraffin so as to facilitate the movement of the pressure fluid.

55 A packer cap 28 rests on the rubber 17 and a conduit 29 extends from the cap 28 60 through the rubber 17 to the space between the packing. A conduit 30 leads from the cap 28 through the casing head 6 and is connected by a conduit 31 with a conduit 32 connected to the T 26 and thence to a source of 65 supply.

65 Pressure gauges 33 are arranged on each of the lines 31, 18a and 19 and each are provided with valves 34. By manipulating these valves, the pressure delivery to each of the 70 sands may be controlled as some of the sands are usually very much more open than others. Unless such control is used practically all the fluid will be delivered to some one sand. Check valves 35 are also arranged in each 75 of the lines 31, 18a and 19 preventing a back-flow from one sand to another when pressure is off the supply line.

80 With this apparatus controlled pressure may be delivered to each of the sands and this 80 is readily accomplished through a single well, thus making the operation of the wells to which the oil is delivered much simpler than where separate pressure wells are used and also the installation is very much cheapened 85 and the pressure supply may thus be localized.

85 What I claim as new is:—

90 1. In a pressure apparatus for oil sands, the combination of a packer between two 100

sands; a fluid pressure tube leading through the packer; and means delivering fluid pressure to the well and above the packer comprising a pipe within the tube, and a fitting forming a discharge for the pipe and a bypass continuing the tube.

5 2. In a pressure apparatus for oil sands, the combination of a packer between two sands; a fluid pressure tube leading through the packer; and means delivering fluid pressure to the well and above the packer comprising a pipe within the tube and a fitting forming a discharge for the pipe and continuing the tube, said discharge of the fitting being radial toward the sand.

10 3. In a pressure apparatus for oil sands, the combination of a packer between two sands; a fluid pressure tube leading through the packer; means delivering fluid pressure to the well and above the packer comprising a pipe within the tube, and a fitting forming a discharge for the pipe and a bypass continuing the tube; and a second packer above the fitting.

15 4. In a pressure apparatus for oil sands, the combination of a packer between two sands; a fluid pressure tube leading through the packer; means delivering fluid pressure to the well and above the packer comprising a pipe within the tube, and a fitting forming a discharge for the pipe and a bypass continuing the tube; a second packer above the fitting; and devices delivering fluid under pressure above the second packer.

20 5. In a pressure apparatus for oil sands, the combination of a packer between two sands; a fluid pressure tube leading through the packer; means delivering fluid pressure to the well and above the packer comprising a pipe within the tube, and a fitting forming a discharge for the pipe and a bypass continuing the tube; a second packer above the fitting; and devices delivering fluid under pressure above the second packer comprising a conduit outside of the tube.

25 6. In a pressure apparatus for oil sands, the combination of a packer between two sands; a fluid pressure tube leading through the packer; means delivering fluid pressure to the well and above the packer comprising a pipe within the tube, and a fitting forming a discharge for the pipe and continuing the tube; a second packer above the fitting; and devices delivering fluid under pressure above the second packer comprising a conduit outside of the tube, and a packer through which the conduit extends.

In testimony whereof I have hereunto set my hand.

CHARLES A. WAITZ.

CERTIFICATE OF CORRECTION.

Patent No. 1,861,332.

May 31, 1932.

CHARLES A. WAITZ.

It is hereby certified that the residence in the above numbered patent was erroneously written and printed as "Erie, Pennsylvania" whereas said residence should have been written and printed as Rouseville, Pennsylvania, as shown by the record of the case in this office; and that the said Letters Patent should be read with this correction therein that the same may conform to the record of the case in the Patent Office.

Signed and sealed this 30th day of August, A. D. 1932.

(Seal)

**M. J. Moore,
Acting Commissioner of Patents.**
